U.S. CL. 260—683.68

6 Claims

ABSTRACT OF THE DISCLOSURE

Paraffinic hydrocarbon feedstocks are contacted with liquid phase superacid systems in the presence of high partial pressures of hydrogen to minimize cracking of reactant paraffinic hydrocarbons to less desirable products and increase the selectivity of the conversion of paraffinic hydrocarbons to skeletal isomers containing the same number of carbon atoms. In one specific embodiment, normal heptane-containing hydrocarbon feedstocks are contacted with a liquid phase catalyst system comprising at least one Group Vb fluoride selected from arsenic pentafluoride, antimony pentafluoride, and mixtures thereof and at least one of trifluoromethanesulfonic acid and HF in the presence of sufficient hydrogen to provide a hydrogen partial pressure of at least about 900 p.s.i.g. to yield with good selectivity C_7 isomers of heptane.

This invention relates to hydrocarbon conversion. In accordance with another aspect, normal paraffins are isomerized with high selectivity to skeletal isomers containing the same number of carbon atoms by contacting with a liquid phase catalyst system comprising a Group Vb fluoride and an acid at high hydrogen partial pressures of at least about 900 p.s.i.g. to suppress cracking and increase selectivity. In accordance with a further aspect, this invention relates to an improved process for the skeletal isomerization of normal paraffins in the presence of a liquid phase catalyst system comprising a Group Vb fluoride and at least one of trifluoromethanesulfonic acid and HF at hydrogen partial pressures of at least about 900 p.s.i.g. to suppress cracking and increase selectivity to skeletal isomers containing the same number of carbon atoms. In accordance with a further aspect, this invention relates to the isomerization of normal heptane with high selectivity to C_7 isomers by contacting with a liquid phase superacid system in the presence of sufficient hydrogen to provide a hydrogen partial pressure in the range 1000–2000 p.s.i.g.

It is well known that the more highly branched isomers of the paraffinic hydrocarbons occurring in petroleum gasoline fractions are more valuable than the corresponding slightly branched or straight chain hydrocarbons because of their higher octane ratings. The demand for motor fuels of greater octane number has increased markedly as the automotive industry has provided gasoline engines with increasingly higher compression ratios to attain greater efficiency. One of the economically important ways in which the increased demands for high octane fuels can be met is through the isomerization of the light naphtha components of such fuels.

It may be generally stated that the isoparaffinic and branched chain paraffinic hydrocarbons are of greater commercial value to the petroleum industry than the corresponding straight chain hydrocarbons. Thus, for example, 2,2-dimethylbutane has a higher octane rating than the isomeric normal hexane. Isobutane is more valuable than normal butane since the former can be used as a basis for the preparation of 8-carbon atom, branched chain hydrocarbons by alkylation with butylene.

2

The isomerization of normal paraffin hydrocarbons into the corresponding branched chain homologs is well known. For effecting the isomerization, it is customary to employ certain metal halides, particularly aluminum chloride or aluminum bromide, in conjunction with certain promoters such as hydrogen chloride, hydrogen bromide, or boron fluoride. Recently, strong acid systems such as solutions of fluorosulfonic acid and antimony pentafluoride have also been disclosed as useful isomerization catalysts. An important problem arising with the use of these highly active catalysts is that they promote side reactions such as cracking and disproportionation. These side reactions are particularly evident at high conversion conditions and lead to the formation of substantial amounts of undesirable light and/or heavy side products.

Accordingly, an object of this invention is to provide an improved hydrocarbon conversion process.

Another object of this invention is to provide an isomerization process whereby high selectivity to skeletal paraffinic isomers is achieved.

A further object of this invention is to provide an isomerization process whereby cracking to undesirable products is minimized.

A further object of this invention is to provide an improved isomerization process for the conversion of paraffinic hydrocarbon to skeletal isomers with high selectivity.

Another object of this invention is to provide an improved isomerization process for the conversion of normal heptane with high selectivity to skeletal isomers.

Other objects and aspects as well as the several advantages of the invention will be apparent to those skilled in the art upon further consideration of the specification and the appended claims.

In accordance with the invention, it has been found that paraffinic hydrocarbons can be isomerized to skeletal isomers with high selectivity with minimum cracking by conducting the isomerization with liquid phase superacid catalyst systems in the presence of high hydrogen partial pressures above about 900 p.s.i.g.

Further in accordance with the invention, it has been found that normal paraffins can be isomerized with high selectivity to branched isomers containing the same number of carbon atoms by contacting paraffinic hydrocarbon-containing feedstocks with a liquid phase catalyst comprising at least one Group Vb fluoride selected from arsenic pentafluoride, antimony pentafluoride, and mixtures thereof and at least one of trifluoromethanesulfonic acid and hydrogen fluoride under hydrogen partial pressures ranging from 900 to 4000 p.s.i.g. to suppress cracking of paraffinic reactants to less desirable cracked products and increase selectivity to desired isomeric products.

In accordance with one specific embodiment, normal heptane isomerizes with high selectivity to branched C_7 isomers by contacting with a liquid phase catalyst comprising either antimony pentafluoride or arsenic pentafluoride and HF or trifluoromethanesulfonic acid at hydrogen partial pressures in the range 1000–2000 p.s.i.g.

In accordance with another embodiment, 2-methylhexane is isomerized to C_7 isomers with good selectivity by contacting with a liquid phase catalyst system comprising antimony pentafluoride and hydrogen fluoride at hydrogen partial pressures in the range 1000–2000 p.s.i.g.

Suitable paraffinic hydrocarbon-containing feedstocks for the purposes of the present invention will contain normal paraffinic hydrocarbons having from 4 to 8, inclusive, carbon atoms in the molecule and can be exemplified by normal butane, normal pentane, normal hexane, normal heptane, normal octane, and the like. While the feed can substantially comprise a purified normal paraffinic hydrocarbon stream, it is also contemplated that mixtures of various paraffic hydrocarbons can be employed.

One component of the liquid phase catalyst system of the present invention comprises a fluoride of a Group Vb element. Specific examples of these fluorides include antimony pentafluoride and arsenic pentafluoride, as well as mixture thereof.

The catalyst composition of the present invention also comprises trifluoromethanesulfonic acid and/or HF.

As indicated above, the formation of undesirable side products can be suppressed and the selectivity to desired skeletal isomers can be increased by carrying out the isomerization in the presence of at least 900 p.s.i.g. of hydrogen pressure. The hydrogen pressure can vary from 900 to 4000 p.s.i.g., but with pressures generally in excess of 2000 p.s.i.g. hydrocarbon conversion decreases. Accordingly, it is preferred to carry out the isomerization reaction at hydrogen partial pressures in the range 1000-2000 p.s.i.g.

The reaction conditions for isomerization of the feed can be in the range of 0 to 100° C., usually 15 to 65° C., and pressure sufficient to maintain the hydrocarbon reactants and catalysts as liquids in the reaction zone and the temperatures and pressures should be chosen accordingly. The time of contact is subject to wide variation, the length of residence time dependent in part upon the temperature and catalyst concentration employed. In general, contact times ranging from about 5 minutes to 48 hours, preferably 15 minutes to about 2 hours, are employed.

The mole ratio of paraffinic hydrocarbon to Group Vb fluoride forming the catalyst of the invention will generally be in the range 50:1 to 0.2:1, preferably 1:1 to 20:1. The mole ratio of trifluoromethanesulfonic acid or HF to Group Vb fluoride catalyst components will generally be in the range 100:1 to 0.2:1, preferably 1:1 to 20:1.

The process of the invention is conducted as a batch

4 SPECIFIC EXAMPLES

In the practice of this invention, the process is carried out in a 30 ml. Hastelloy B autoclave. Antimony pentafluoride and arsenic pentafluoride which are very hygroscopic and fume profusely in air were weighed and transferred under a nitrogen atmosphere. The antimony pentafluoride or arsenic pentafluoride and liquid hydrogen fluoride or trifluoromethanesulfonic acid were then mixed and transferred to the reactor at ice bath temperature.

Normal heptane was added and the reactor was pressured with the desired amount of hydrogen. The reactor was heated by means of a water bath to the desired temperature for the specified period of time.

Workup involved cooling the Hastelloy B autoclave in Dry Ice-acetone, venting the hydrogen, and then rapidly pouring the cold mixture into a Teflon separatory funnel. The upper hydrocarbon layer was drained into a cold (Dry Ice-acetone temperature) Fischer-Porter aerosol compatibility bottle containing about 5 grams of potassium carbonate. The bottle was quickly capped with a head equipped with a pressure gage and a silicone septum for withdrawing glc samples. Results were reported as selectivities based on the glc (gas-liquid chromatography) analyses.

A liquid catalyst system comprising antimony pentafluoride and HF was used to effect the isomerization of normal heptane in accordance with the procedure set forth above at varying hydrogen partial pressures. The isomerization was effected at a temperature of 25° C. for a period of three hours. Approximately 0.5 mole n-heptane, 50 ml. HF, and 0.5 mole SbF₅ were used in each run. The results of the normal heptane isomerization are given below in Table I.

TABLE I
Isomerization of normal heptane with liquid Sb₅/HF at 25° C.

Run	n-C ₇ percent conversion	H ₂ , p.s.i.g.	C ₃	C ₄ 's	C ₅ 's	C ₆ 's	C ₇ 's	Heavies	Total cracking
1	96.0	0	3.0	30.0	24.0	21.0	9.0	13.0	91.0
2	99.0	400	4.3	35.8	25.6	21.6	10.3	2.4	89.7
3	99.4	700	10.2	49.3	6.8	6.4	18.2	0.1	81.8
4	98.6	1,000	25.5	43.7	0.5	0.6	29.7	Trace	70.3
5	96.0	1,500	15.0	34.0	Trace	Trace	50.0	0.0	49.0
6	96.0	1,600	20.0	28.0	1.0	1.0	50.0	0.0	50.0
7	53.0	2,000	9.2	14.3	1.0	1.1	74.4	0.0	25.6
8	15.2	2,700	9.3	14.3	3.1	1.2	71.7	0.4	28.3
9	9.3	4,000	9.2	13.7	5.9	1.9	69.4	0.0	30.7

or a continuous operation. The apparatus employed can be of a conventional nature and can comprise a single reactor equipped with sufficient stirring devices. Good agitation is important because the less dense paraffinic hydrocarbon layer is not miscible with the denser liquid acid phase. Unreacted reactants, catalyst and other products of the reaction can be separated from the desired product and from one another such as by distillation and returned in whole or in part to the isomerization zone. The resultant product can be further processed as by alkylation and the like or be employed directly as a high octane gasoline blending agent. The reaction zone is preferably constructed of materials which are resistant to corrosion by the catalyst. For example, the reactor can be a Monel lined reactor. It is preferred that the reaction be carried out under anhydrous conditions in an inert atmosphere. Trifluoromethanesulfonic acid fumes copiously upon exposure to air and the Group Vb halides are also hydrolyzed on exposure to atmospheric moisture.

Referring to the above table, it will be observed that conversion drops off rapidly above 2000 p.s.i.g. hydrogen whereas the selectivity to isomerized C₇'s remains high. It is to be further noted from the above table that Runs 5 and 6, which were carried out at 1500 and 1600 p.s.i.g. hydrogen, result in 96 percent n-C₇ conversion with a selectivity of 50 percent to C₇ and the formation of no heavies. It will also be observed from the above table that although heptane conversion was high for Runs 1 and 2, the total cracking was also above 90 percent. It will be observed from the above table that 400 p.s.i.g. hydrogen did not reduce the selectivity to cracking as compared to 0 p.s.i.g. hydrogen. Runs carried out at 1500-16000 p.s.i.g. hydrogen reduces selectivity to cracking to about 50 percent. Little or no acid soluble oils were formed and selectivity to heavies in Runs 3 through 9 was less than 0.5 percent.

The extent of n-heptane isomerization is shown by the relative weight percentages of the C₇ isomers in Table II below.

TABLE II.—RELATIVE WEIGHT PERCENTAGES OF COMPONENTS* IN

Run	THE HEPTANE FRACTION								
	2,2-DMP	2,4-DMP	2,2,3-TMB	3,3-DMP	2-MH	2,3-DMP	3-MP	3-EP	n-C ₇
3	40.65	11.35	5.43	8.87	14.89	5.54	9.87	0.38	3.07
4	20.31	14.99	7.41	11.76	19.97	7.25	13.18	0.42	4.72
5	14.84	15.07	7.37	11.51	20.72	7.49	13.90	0.45	8.65
6	27.16	27.16	7.92	33.72	33.72	23.85	23.35	0.44	7.40
7	0.83	9.61	4.16	1.18	13.93	5.55	10.05	0.34	54.35
8	0.10	2.41	0.86	0.11	3.78	1.37	2.62	0.09	88.66
9	0.05	1.43	0.49	0.05	2.21	0.83	1.54	0.05	93.35

*The following abbreviations are used in Table II: 2,2-DMP for 2,2-dimethylpentane; 2,4-DMP for 2,4-dimethylpentane; 2,2,3-TMB for 2,2,3-trimethylbutane; 3,3-DMP for 3,3-dimethylpentane; 2,3-DMP for 2,3-dimethylpentane; 2-MH for 2-methylhexane; 3-MH for 3-methylhexane; 3-EP for 3-ethylpentane; n-C₇ for normal heptane.

EXAMPLE II

Normal heptane was isomerized to its branched isomers by contacting with a mixture of antimony pentafluoride and trifluoromethanesulfonic acid (Run 10) and arsenic pentafluoride and HF (Run 11) at approximately 25° C. for three hours in the presence of high hydrogen partial pressures. In Run 10, 0.055 mole of antimony pentafluoride, 0.5 mole n-heptane and 50 ml. (84 g., 0.56 mole) of trifluoromethanesulfonic acid were used. In Run 11, 0.053 mole of arsenic pentafluoride, 0.5 mole of n-heptane and 50 ml. of HF were used. Results of the isomerization of normal heptane are given below in Table III.

TABLE III

Run	Catalyst	Temp., °C.	Time, hours	H ₂ , p.s.i.g.	n-C ₇ percent conversion	Percent selectivities					
						C ₃	C ₄ 's	C ₅ 's	C ₆ 's	C ₇ 's	Heavies
10	SbF ₅ /CF ₃ SO ₃ H	30	3.0	1,500	96.8	14.9	26.0	0.5	0.8	56.6	0.0
11	AsF ₅ /HF	23-25	3.0	1,500	95.0	23.9	45.0	0.6	0.8	29.4	0.0

It will be observed from the above runs that good selectivity to C₇'s was observed with no formation of heavies.

EXAMPLE III

In another run 2-methylhexane was isomerized to its branched isomers by contacting with a liquid catalyst mixture of antimony pentafluoride and hydrogen fluoride under high hydrogen partial pressure. In the run, 0.052 mole of antimony pentafluoride, 0.5 mole of 2-methylhexane and 50 ml. of HF were used. Results of the isomerization are given below in Table IV.

TABLE IV
Reaction of 2-methylhexane with SbF₅/HF

2-MH Percent Conversion	H ₂ , p.s.i.g.	Selectivities*												
		C ₃	C ₄ 's	C ₅ 's	C ₆ 's	n-C ₇	2,2-DMP	2,4-DMP	2,2,3-TMB	3,3-DMP	2,3-DMP	3-MH	3-EP	Heavies
88.0	1,500	20.3	31.7	0.5	0.7	3.1	5.3	10.3	5.6	6.3	6.0	9.9	0.5	0.0

*For abbreviations used in this table see footnote at bottom of Table II.

As demonstrated by the above example, branched isomers of n-heptane such as 2-methylhexane or 3-methylhexane can be used alone or in admixture with normal heptane in the present process.

In the above examples it will be noted that the extent of cracking is shown by the sum of

$$(C_3 + C_4's + C_5's + C_6's + \text{Heavies}).$$

We claim:

1. An improved alkane isomerization process which comprises isomerizing normal paraffins having from 4 to 8, inclusive, carbon atoms to skeletal isomers containing

the same number of carbon atoms by contacting the paraffins under isomerization conditions with a liquid phase catalyst selected from the group consisting of arsenic

pentafluoride, antimony pentafluoride, and mixtures thereof with either trifluoromethanesulfonic acid or hydrogen in the presence of sufficient hydrogen to provide a hydrogen partial pressure of 900-4000 p.s.i.g. during said isomerization to suppress cracking of paraffinic reactants to less desirable cracked products and increase selectively to desired isomeric products.

2. A process according to claim 1 wherein the paraffinic hydrocarbon comprises normal heptane and the hydrogen partial pressure is in the range 1000-2000 p.s.i.g.

3. A process according to claim 1 wherein the isomerization is conducted at a temperature in the range 0-100° C., with a paraffinic hydrocarbon to Group Vb

fluoride mole ratio of 50:1 to 0.2:1 and a trifluoromethanesulfonic acid or HF to Group Vb fluoride mole ratio in the range 100:1 to 0.2:1.

4. A process according to claim 1 wherein said paraffinic hydrocarbon comprises 2-methylhexane, the hydrogen partial pressure is in the range 1000-2000 p.s.i.g., and the liquid phase catalyst comprises antimony pentafluoride and HF.

5. A process according to claim 2 wherein the liquid phase catalyst is antimony pentafluoride with either hydrogen fluoride or trifluoromethanesulfonic acid.
